GEORGES EUGÈNE CANHAC, OF ST.-DENIS, FRANCE, ASSIGNOR TO SOCIETE ANONYME
DES ETABLISSEMENTS DELAUNAY BELLEVILLE, OF ST.-DENIS, FRANCE.

ARRANGEMENT FOR IMPROVING THE WORKING OF EIGHT-CYLINDER TWO-CYCLE INTERNAL-COMBUSTION ENGINES.

1,217,151.

Specification of Letters Patent. Patented Feb. 27, 1917.

Application filed March 30, 1916. Serial No. 87,775.

To all whom it may concern:

Be it known that I, GEORGES EUGÈNE CANHAC, engineer, of Rue de l'Ermitage, at St.-Denis, Department of the Seine, France, 5 citizen of the French Republic, have invented certain new and useful Improvements in Arrangements for Improving the Working of Eight-Cylinder Two-Cycle Internal-Combustion Engines; and I do hereby declare the following to be a full, clear, and exact description of the invention, such as will enable others skilled in the art to which it appertains to make and use the same.

15 This invention relates to engines working on the two-stroke cycle and having four, six or eight cylinders. The crank angles that give the best results from the point of view of uniformity of torque and of the 20 balancing of the engine are known. The application to two-stroke-cycle motors of rules based on four-stroke-cycle motors does not enable the increase in the number of working strokes to improve the uniformity 25 of the torque. Furthermore, when the scavenging air of two-cycle motors is supplied by compressors independent of the motor-cylinders, new difficulties in balancing arise and thus complicate the problem. The 30 masses of the compressor-pistons and of their connecting rods are large enough to bring inertia forces into play that cannot be neglected. The inertia forces of the compressors cannot always be balanced among 35 themselves, and one is constrained either to combine the balancing of the inertia forces of the pumps with those of the engine, in which case the balance calculations lead to setting the engine cranks at angles that are 40 not the most favorable to uniformity of torque; or else to add moving balance weights, which have the disadvantage of increasing the weight of the motor. Another 45 difficulty peculiar to two-cycle motors with scavenging compressors is the choice of the position of the compressors, which should be such that the passages leading from the pump cylinders to the motor cylinders are as short as possible, so that the loss of pressure 50 sure in the scavenging air may be very slight. This consideration is particularly important.

This invention relates to means for overcoming all these difficulties in the case of two-stroke cycle eight-cylinder Diesel engines with two scavenging air compressors and two blast air compressors.

Figure 1 is a diagram illustrating the improved system of construction.

Fig. 2 is a balance diagram of this motor. 60 Entirely satisfactory results are obtained if the motor and compressor cylinders are arranged according to the plan shown in Fig. 1, if the motor cranks are keyed at 45° from one another, and if the setting of the 65 engine crank and that of the compressor cranks are appropriately related to one another.

Each scavenging compressor is placed between two groups of two working cylinders. 70 The usual single scavenging collector is replaced by four sections each having a quarter of the length and a quarter of the discharge. The resistance to the motion of the air being proportional to the square of the 75 velocity and to the length of the passage, for scavenging passages of the same cross section, the arrangement shown in Fig. 1 offers only one-sixty-fourth of the resistance offered by that where the single collector is 80 used.

The uniformity of torque is as great as possible, on account of the cranks being keyed at 45°, because the various cylinders produce their turning effort successively and 85 never simultaneously.

The appropriate combination of the setting of the engine and compressor cranks enables a perfect balance to be obtained.

The cranks of the motor cylinders M_1 and M_2 are set at 180° from one another. These elements being exactly alike, their inertia forces balance, and no inertia moment remains. Similarly the inertia forces of the motor cylinders M_3 and M_4 , M_5 and M_6 , M_7 and M_8 , the scavenging air compressors B_1 and B_2 , and the blast air compressors I_1 and I_2 , balance one another in pairs. The moment of inertia of the two cylinders M_1 and M_2 is positive and reaches a maximum when 100 one of its cranks, (that of M_1 for example) is at its upper dead center. It remains positive until the piston of M_1 reaches the middle of its stroke. Then it becomes negative,

reaches its minimum when the piston of M_1 is at its lower dead center, remains negative until the piston passes the mid-point of its stroke, then becomes positive, and again reaches its maximum when the piston is at its upper dead center. In other words the moment of inertia may be represented by a revolving vector that remains constantly parallel to the cranks M_1 and M_2 , the direction of the arm of the crank M_1 being reckoned positive. The moment of inertia of each group of cylinders M_3 and M_4 , M_5 and M_6 , M_7 and M_8 , may similarly be represented by the projections of a revolving vector. All these vectors are equal to one another, because the motor elements are all of the same weight, and the distances between the axes in each group of two cylinders are the same. The moments of inertia of the compressor elements B_1 and B_2 , I_1 and I_2 can also be represented by revolving vectors, but the latter are not equal either to one another or to the vectors of the motor elements.

It is thus possible to draw the diagram shown in Fig. 5, in which M_1 , M_2 . . . M_8 represent the simultaneous positions of the eight crank pins. OM_1 , OM_2 , OM_5 , OM_7 are the four vectors representing the moments of inertia of the motor elements. OM_1 and OM_5 have a resultant along OR' , and OM_3 and OM_7 have a resultant along OR'' . The two resistances OR' and OR'' themselves have a resultant OR . All the moments of inertia of the motor elements lead therefore to a moment which is not much greater than the moment of two adjacent elements set at 180° , which can be balanced by means of the compressor elements. The two scavenging air compressors should be set so that their crank pins are at B_1 and B_2 , in the straight line OR . These elements are in practice lighter than the motor elements, but the distance between the two compressors is greater than that between two adjacent engine cylinders, and their moment of inertia is a little greater than OR . Most of this difference can be compensated for by means of the moment of inertia of the blast air compressors, by placing their crank pins at I_1 and I_2 .

Copies of this patent may be obtained for five cents each, by addressing the "Commissioner of Patents, Washington, D. C."

and I_2 . The slight difference that remains 50 can be corrected by supplementary masses, but in general this correction is superfluous.

Other positions of the cranks enable the same balance to be obtained. M_1 and M_2 can be replaced by M_3 and M_4 respectively, 55 and inversely, without changing the moment of inertia diagram, but M_2 cannot be substituted for M_1 , and inversely. All the crank angles that produce balance are such that the odd motor cylinders are set at $22^\circ 30'$ 60 and $112^\circ 30'$ before or behind the crank of the first scavenging air compressor.

Claims:

1. A two-stroke cycle engine of the Diesel type, consisting of eight working cylinders, 65 two scavenging air compressors and two blast air compressors, the cylinders being grouped so that four of the working cylinders are located adjacent to a compressor cylinder and the other four are located at a 70 distance from a compressor not exceeding the width of a cylinder.

2. A two-stroke cycle engine of the Diesel type, consisting of eight working cylinders, 75 two scavenging air compressors, two blast air compressors, a piston in each of the cylinders and in each of the compressors, a crank-shaft and a piston-rod connected to each piston and to the shaft, the eight driving cranks being set at 45° from one another 80 and the four compressor cranks being set in a plane that bisects one of the dihedral angles of 45° formed by the planes containing the driving cranks, the cranks of the two scavenging air compressors being opposite 85 to one another and also those of the blast air compressors, the odd driving cranks being set at $22^\circ 30'$ or $112^\circ 30'$ before or behind the crank of the first scavenging air compressor, and each even driving crank being 90 opposite to the immediately preceding odd crank.

In testimony whereof I affix my signature, in presence of two witnesses.

GEORGES EUGÈNE CANHAC.
